UNITED STATES PATENT OFFICE

2,493,166

FOAM SKIMMER

Henry A. Schmitz, Jr., Shorewood, Wis., assignor
to A. O. Smith Corporation, Milwaukee, Wis.,
a corporation of New York

Application January 24, 1946, Serial No. 643,166

3 Claims. (Cl. 210—51)

1

This invention relates to a foam skimmer and has particular relation to a foam skimmer for a closed fermenting tank such as is employed in the manufacture of beer and the like.

The principal object of the invention is to provide a receptacle within one side of a fermenting tank and adjacent the top thereof at a level to catch scum and foam from the liquid being fermented in the tank.

Another object is to provide a receptacle to receive and retain foam and scum that does not decrease the fermenting space within the tank.

A further object is to provide a receptacle for skimming foam off from fermented liquid within a tank that provides for ready removal of the foam.

Another object is to provide a foam skimmer permitting removal of foam and scum while the tank is in operation.

These and other objects of the invention will appear hereinafter in connection with the following description and the accompanying drawing illustrating the invention.

In the drawing:

Figure 1 is a longitudinal sectional view of the foam skimmer of the invention and a portion of a tank with the door to the skimmer receptacle in closed position;

Fig. 2 is a similar view with the door open;

Fig. 3 is an end view with the door closed;

Fig. 4 is a top plan view with parts broken away and sectioned with the door closed and the skimmer receptacle welded to the front wall; and

Fig. 5 is a top diagonal view of the tank with the door open and the skimmer receptacle welded to the front and side walls of the tank.

Referring to the drawings there is illustrated a portion of a tank 1, such as a beer tank, lined with ceramic enamel 2 or the like to prevent injury to the beer and corrosion by the contents of the tank and within which at one end and adjacent the top 3 thereof, is assembled a skimmer receptacle 4 access to which is gained by the closure door 5.

The receptacle 4 is secured to one side of the tank a substantial distance below the top 3 and directly beneath the cleanout opening 6 closed by door 5. Opening 6 also is employed to work through if receptacle 4 is coated with ceramic enamel or the like.

The skimmer receptacle is formed from suitable metal and comprises a plate that is joined to the front wall of the tank 1, such as by welds 7,

2

and projects inwardly from the wall of the tank. Receptacle 4 is shown as being of stainless steel but it may be a receptacle protected from corrosion by a coating of ceramic enamel.

The inner end portion 8 of the receptacle 4 curves upwardly and the sides 9 are also upwardly curved. The peripheral edge 10 is disposed slightly above the normal level of the fermenting liquid contained within the tank and is at a level at which scum and foam forced upwardly within the liquid in the fermenting process will flow over the same and be caught and retained within receptacle 4.

A drain opening is provided in the bottom of receptacle 4 and the removable plug 11 is disposed therein to permit draining and cleaning of the receptacle when tank 1 is empty.

The receptacle 4 is preferably formed with a slight slope in the bottom portion toward the cleanout opening 6 and the drain to more readily provide for cleaning out the receptacle or draining of the receptacle when plug 11 is removed.

The opening 6 or entrance to receptacle 4 is closed in operation by the door 5 when liquid is fermenting in the tank.

The door 5 is held securely against the inside of the wall of the tank around opening 6 by a plurality of latches 12 which are pivoted to the outer wall of the tank adjacent opening 6 and disposed to interlock with the matching lugs 13 secured to the door. The handle on each latch 12 provides for ready manipulation thereof.

The joint between the door and wall is sealed by a suitable gasket 14 of rubber or the like.

A curved lever arm 15 is secured at one end to the center of door 5 and at the other end the arm is pivoted to the wall of tank 1 at a suitable distance above the door and on a vertical line through the center thereof.

A handle 16 extends outwardly of the upper portion of arm 15 and is grasped and pushed upwardly by the operator to swing door 5 closed through a downward arc, or pulled downwardly to push the door open and upwardly through an upward arc.

A pipe 17 leads from receptacle 4 to any suitable container, not shown, and foam trapped in the receptacle when liquid is fermenting in the tank is drained off by opening stopcock 18.

The embodiment of the invention illustrated in Fig. 5 is similar to the embodiment previously described, except that the skimmer receptacle 4 extends completely across the tank and is welded to the front and side walls of the tank by welds 19. The tank walls cooperate with receptacle 4

50 55

to retain the foam and scum within the receptacle until the foam is removed.

In operation, the liquid to be fermented is disposed in tank 1 through a suitable opening not shown, until it reaches a level slightly below that of the inner peripheral edge 10 of the skimmer receptacle 4.

The cleanout opening 6 is closed by door 5 which is sealed against the inner wall of the tank by gasket 14 when latches 12 are interlocked with lugs 13.

As the contained liquid ferments scum and foam are forced upwardly and flow over the edge 10 into receptacle 4.

From time to time stopcock 18 is opened and foam and scum is drained from receptacle 4 through pipe 17 leading to any suitable disposal unit.

When the fermentation of the liquid within the tank is completed the liquid is removed and skimmer receptacle 4 may be cleaned through opening 6 after swinging door 5 to open position. Plug 11 may also be removed to completely drain the receptacle.

Other openings, not shown, are provided in tank 1 to flush and clean the tank when it is empty.

The invention provides a foam skimmer that does not take up any substantial space within the tank and from which foam and scum may be readily removed.

Various embodiments of the invention may be employed within the scope of the following claims.

I claim:

1. In combination with a fermenting tank, a foam skimmer comprising a receptacle suspended within said tank and formed of a plate upwardly curved around the entire inner portion thereof and with the outer portion of the plate secured to the tank wall, the periphery of the curved portion of the receptacle being disposed slightly above the surface of the fermenting liquid within the tank to permit flow of foam and scum thereover into the receptacle when foam and scum is forced to the surface of the liquid in the fermenting process, means providing access into said receptacle for removal of foam and scum through an opening in the wall of the tank directly above the bottom of said receptacle, means to seal said latter means closed when the liquid is fermenting, and means to remove foam from said receptacle when the tank is sealed during fermentation of liquid therein.

2. In combination with a closed fermenting tank, a foam skimmer comprising a receptacle welded to the inside of the tank wall beneath an

opening in the wall for access thereto for clean-out purposes and projecting inwardly a substantial distance from the wall with the inner edge slightly above the surface of the liquid fermenting within the tank to permit overflow into the receptacle of foam and scum forced to the surface of the liquid in the fermentation process, a door on the inside of said tank for closing said opening, a curved lever arm secured at one end to said door and pivoted at the other end to the outside of the tank wall above said opening to swing said door inwardly to open the same and outwardly to close the same, a plurality of latch members to lock said door in closed position when liquid is fermenting within the tank, and a drain pipe leading from said receptacle to drain foam and scum therefrom when the tank is sealed during fermenting of liquid therein.

3. In combination with a closed fermenting tank, a foam skimmer comprising a receptacle welded to the inside of the tank wall directly beneath an opening in the wall for access thereto and projecting inwardly a substantial distance from the wall with the inner edge slightly above the surface of the liquid fermenting within the tank to permit overflow into the receptacle of foam and scum forced to the surface of the liquid in the fermentation process, said receptacle being formed with the bottom sloping toward said opening and provided with a removable plug in the bottom thereof for cleanout purposes, and a door disposed to seal said opening and to swing away therefrom to permit access to the receptacle for removal of foam and scum therefrom after the liquid fermented in the tank is removed therefrom, and means to remove foam from said receptacle when the tank is sealed during fermentation of liquid therein.

HENRY A. SCHMITZ, JR.
